UNITED STATES PATENT OFFICE.

FRANK G. JUNNEY, OF VICTOR, NEW YORK.

POTATO-COVERER.

SPECIFICATION forming part of Letters Patent No. 297,266, dated April 22, 1884.

Application filed January 24, 1883. (No model.)

To all whom it may concern:

Be it known that I, FRANK G. JUNNEY, of Victor, Ontario county, New York, have invented certain Improvements in Machines for Covering Potatoes, &c., of which the following is a specification, reference being had to the annexed drawings.

My improvements in machines for covering potatoes, &c., are represented in the accompanying drawings, in which—

Figure 1 is a side elevation. Fig. 2 is a plan view. Fig. 3 is a front elevation. Fig. 4 is a side elevation of one of the mold-boards detached, as seen from the inner side. Fig. 5 represents in elevation one of the angle-pieces by which the mold-boards are adjustably connected with the cross-bars. Fig. 6 is a side view of the same. Fig. 7 is a side elevation of the coverer. Fig. 8 is a section through one 20 of the mold-boards on the line $z z$, Fig. 4.

My improved machine for covering potatoes or other similar purposes consists of two inclined mold-boards, A A', adjustably secured to the cross-bars B and C, a yielding coverer, D, and offset-handles E E', the whole structure being arranged to throw the earth inward into a ridge over the articles to be planted when drawn forward over the ground and to smooth down the surface of the soil in rear of the machine. The mold-boards A A' are formed of wood of suitable thickness, and made of curved form on their lower edges, being shod with the metallic shares F F', which are secured to the wood by screws or bolts, and project a short 35 distance below the mold-boards. The mold-boards and shares are inclined to each other not only in the horizontal but also in the vertical direction, as represented in the drawings, Fig. 2, their lower edges being nearer together 40 than their upper edges, for the purpose of more effectually gathering and throwing inward the earth. The mold-boards are attached together so that the horizontal angle between them may be varied by means of the cross-bar B and the 45 slotted angle-plate $n n' n'' n'''$.

The form of the angle-plates is shown in the drawings, Figs. 5, 6, and 8, they being made of such shape as to be applied to both the inner and outer sides of the mold-boards. The 50 angle-plates are secured to the mold-boards in such position that their uppersides come flush with the top of the mold-boards by means of a

bolt, r , Figs. 1 and 4, passing through holes s , Fig. 5, in the angle-plates. For the purpose of securing sufficient strength, the angle-plates are provided with the flanges $t t$, Figs. 5 and 6. The upper sides of the angle-plates are provided with slots u , Fig. 5, through which pass the bolts $v v v v$, by which the angle-plates are adjustably secured to the cross-bar B. The angle between the mold-boards A and A' is readily changed by slackening the nuts on the bolts $v v$ and moving the boards into the desired position, the bolts sliding along in the slot u , and then securing the mold-boards to the cross-bar by screwing down on the nuts. The adjustability of the mold-boards relatively to each other in the horizontal plane is indicated by the dotted lines $A'' A'''$ in the drawings, Fig. 2. At their rear ends the mold-boards may be attached to the cross-bar C by slotted angle-plates; but such arrangement is ordinarily unnecessary, and I employ at this point angle-plates similar to those already described, but simply perforated with holes 75 for the reception of the bolts.

Attached to the under side of the front cross-bar, and extending backward and downward, is the yielding coverer D, which is formed of sheet metal of suitable thickness, and has its 80 rear end made to extend outward beyond the mold-boards, as represented in Fig. 2. The outer edges of the coverer toward the rear are bent upward slightly, as represented in the side view, Fig. 7.

To the upper surface of the coverer is attached a stiffening-rib, l , into which is inserted a staple or hook for a chain, h , which reaches upward to the rear cross-bar, for the purpose of holding the coverer in place in backing the 90 machine. The coverer operates to smooth down any inequalities in the earth thrown up by the mold-boards, its attachment to the cross-bar B permitting it to yield slightly for this purpose. The forward end of the sheet-metal coverer is attached to the lower side of the cross-bar B by screws or bolts, the stiffening-rib l terminating in rear of the bar, so as not to interfere with the yielding action of the coverer.

I provide my improved potato-coverer with offset handles E E', to prevent the necessity of the driver walking in the planted row. The handles are of ordinary form, attached at their

forward ends to the front cross-bar by bolts *y*, and supported by braces *m* and *p*, extending upward from the rear cross-bar. The right-hand handle may also be braced from the front 5 cross-bar by the brace *q*. These braces are formed of cast-iron of suitable shape, and secured at each end to the wood-work by bolts. The two braces *m* and *p* may be connected to the rear cross-bar by a single bolt. The front 10 cross-bar is provided with hooks or staples for the attachment of a tongue or thills, I.

I am aware that metallic shares have been heretofore applied to wooden mold-boards; that angle-plates and various other means have been 15 heretofore adopted for varying the angle of inclination between mold-boards arranged to throw the earth or soil toward the central line between them, and that offset handles have been previously employed on machines of various kinds, and such features I do not claim. 20 I am also aware that scrapers or coverers of

various forms have been heretofore applied to seeding-machines for the purpose of smoothing down the surface of the soil behind them, as shown, among others, in the patent of Hobson, 25 No. 120,742, November 7, 1871; and my claim of novelty herein is therefore limited in the combination recited to the specific form of coverer herein described.

I claim—

The combination, with the mold-boards A A', provided with shares F F', of the cross-bars B and C, and the yielding coverer D, formed of sheet metal of suitable thickness, and having its rear edges extended laterally beyond the 35 mold-boards, substantially as and for the purposes specified.

FRANK G. JUNNEY.
